UNITED STATES PATENT OFFICE.

WILLIAM P. ANDERSON, OF NEW YORK, N. Y.

AUTOMATIC SEWAGE-EJECTOR.

1,008,884.

Specification of Letters Patent. Patented Nov. 14, 1911.

Application filed July 6, 1911. Serial No. 637,222.

To all whom it may concern:

Be it known that I, WILLIAM P. ANDERSON, a citizen of the United States, residing at New York city, State of New York, have 5 invented certain new and useful Improvements in Automatic Sewage-Ejectors; and I do hereby declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to new and useful improvements in automatic sewage ejectors in which, while being especially adapted for sewage systems, may be equally well adapted for pumping purposes generally.

20 The invention comprises a simple and efficient apparatus having various details of construction and combinations and arrangements of parts which will be hereinafter fully described and then specifically defined 25 in the appended claim.

I illustrate my invention in the accompanying drawings, in which:—

Figure 1 is a vertical sectional view through a receiver tank. Fig. 2 is a vertical 30 sectional view through the top of the tank showing in edge view operative parts of the apparatus. Fig. 3 is a top plan view, and Fig. 4 is a detail in elevation.

Reference now being had to the details of 35 the drawings by letter, A designates a receiving tank which should be placed sufficiently low to permit drainage by gravity thereto, and is provided with a top B apertured at C for the reception of the compressed air or steam introduction pipe D and also having a suitably packed opening E for the reception of the float rod F having a yoke F' therein which has slots H and H' for the reception of the two levers N and O, 40 the former of which is fastened to the stem L of an inlet valve mounted within the casing L' and with which a supply pipe L² communicates, while the other of said levers is fixed to the stem Q of a vent valve within 45 the casing Q' and which latter communicates with the atmosphere through the pipe Q². The two valve casings communicate with each other through the pipe M.

Rising from the flange B' of the closure 5 or top to the tank are the standards R and pivotally mounted upon the pins R' are the

two angle levers S and T respectively, the former of which has fixed thereto a weight S' and the latter a weight T'. The arm of the lever S is provided with a slot S² for the 60 reception of the lever M and an arm of the lever T is provided with a slot T² for the reception of the lever O. It will be noted upon reference to the drawings that the marginal ends of the slots terminate one 65 above the other while the other ends extend one below the other and provided for the purpose of causing one lever to be operated in advance of the other. Said rod F has 70 fixed thereto stops J and J', and I designates a float having a central opening I' for the reception of said rod. A space intervenes between the wall of the opening I' in the float and the rod in order to allow the float to move freely thereon.

75 In operation, when the float in the receiver rises on the surface of the water within the receiving tank and, when the top of the float comes in contact with the stop J, it will elevate the rod F, the weight of the 80 same and the resistance caused by the packing gland within the top of the receptacle causing the float to be partially submerged, thus permitting the receiver tank to fill to its full capacity. At that point, the lever O 85 being raised by the rod will cause the lever T to tilt upon its pivot R', closing the vent valve within the casing Q' and immediately thereafter the angle lever S will have been tilted by the lever M, thus opening the valve 90 within the casing L' and permitting compressed air or steam, whichever is utilized, to enter through the supply pipe L² and pipe D into the receiving tank, thus discharging the liquid contents by displacement. As the 95 receiver tank empties, the float will travel downward until it strikes the stop J' and which will cause the rod F to be moved downward and the angle levers caused to tilt upon their pivots, said lever S tilting in 100 advance of the lever T, thus causing the valve within the casing M to be closed and shut off the supply of air or steam in advance of opening the vent within the casing Q'. As 105 the vent valve opens, any pressure that may remain within the receiving tank may be discharged, allowing the same to replace. By having the vent valve close first and open last, a loss of pressure through the vent pipe 110 will be prevented which otherwise would occur if both valves opened and closed simultaneously.

What I claim to be new is:—

An automatic sewage ejector apparatus comprising a tank, a top therefor, an air or steam pressure supply pipe leading into the tank, a float rod movable through a suitably packed gland in the cover, stops upon the float rod, a float loosely mounted upon the rod intermediate said stops, a yoke forming a part of said rod and provided with slots, 5 an inlet valve casing and valve in said pipe and valve in the casing, a lever to said valve, a vent valve casing and valve therein, a pipe communicating between the valve casings, 10 said vent valve casing open to the atmos-

phere, a lever connected to the vent valve, 15 said levers extending each through a slot in the yoke, standards rising from the cover, an angle lever pivotally mounted upon each standard, a weight upon one arm of each angle lever, the other arm of each lever provided with a slot for the reception of a lever.

In testimony whereof I hereunto affix my signature in the presence of two witnesses.

WILLIAM P. ANDERSON.
